UNITED STATES PATENT OFFICE

PAUL JAMNITZKY, OF CONEMAUGH, PENNSYLVANIA.

SAFETY DEVICE FOR VESSELS.

No. 893,324.

Specification of Letters Patent.

Patented July 14, 1908.

Application filed April 2, 1908. Serial No. 424,723.

To all whom it may concern:

Be it known that I, PAUL JAMNITZKY, a subject of the King of Hungary, residing at Conemaugh, in the county of Cambria and State of Pennsylvania, have invented certain new and useful Improvements in Safety Devices for Vessels, of which the following is a specification, reference being had therein to the accompanying drawing.

10 This invention relates to a safety device for vessels, and the primary object of my invention is to utilize air as a propelling medium for a boat.

Another object of this invention is to utilize air as a medium to prevent water from entering a vessel that is injured or about to sink.

A still further object of this invention is the provision of novel means in connection 20 with a vessel for dispelling a mist or fog that may surround the same.

With the above and other objects in view which will readily appear as the invention is better understood, the same consists in the 25 novel construction, combination and arrangement of parts to be presently described and then specifically pointed out in the appended claims.

In the drawings, Figure 1 is a diagrammatic view of a large vessel equipped with my safety device, Fig. 2 is a plan of the same, Fig. 3 is a cross sectional view of a vessel taken on the line $x-x$ of Fig. 1, and Fig. 4 is a similar view taken on the line $y-y$ of Fig. 1.

35 Due to the fact that my invention can be used in connection with various kinds of vessels, I have illustrated the same diagrammatically and reserve the right to construct and arrange the device whereby the same can 40 be advantageously used in connection with large ocean liners.

The reference numeral 1 designates the hull of a vessel which is divided into a plurality of compartments 2 and 3 having air-tight partitions 4. In the compartment 2 is arranged a conventional form of engine 5 commonly used for driving the propellers of a vessel. Besides driving the propellers of a vessel, I employ the same to operate air compressors 6, these compressors communicating by pipes 7 with reservoirs 8 and 9. Leading from the reservoirs 8 and 9 into the various compartments of a vessel are pipes 10 having branches 11 controlled by valves 12. Should the vessel be struck and one of the compartments pierced, the compartment

is immediately filled with air to prevent water from entering the same, or should one end of the vessel be injured beyond salvage, the opposite end of the vessel will be filled with air to keep the same afloat, in order that lives and property can be saved.

The bottom of the hull is provided with two longitudinally disposed frames 13 extending from one end of said vessel to the other, said frames being braced, as at 14. These frames are adapted to support the hull of a vessel should the same run aground, as illustrated in Fig. 4 and in order that the hull can be easily floated, I arrange a hinged member 15 at the forward end of the hull, and a hinged member 16 at the rear end thereof, these members when closed provide a compartment beneath the vessel which can be filled with air for floating said vessel. Upon the vessel running ashore divers can close the members 15 and 16 from the outside of a vessel or can enter the compartment 17 beneath the vessel by trap doors 18 hinged in the bottom of the vessel. After the doors 19 are closed, air is admitted to the compartments 17 through hoods 19 communicating with the reservoirs 8 and 9. These hoods are provided with gates 20 and 21. The air within the reservoirs 8 and 9 can be used for propelling the boat, and when traveling in the direction indicated by the bow in Fig. 1 of the drawings, the gates 21 are closed and the gates 20 opened, allowing the ejected air to force the vessel forward. Should the vessel become fog bound, a supply of air from the reservoir 9 is admitted to a frame 22 arranged upon the deck of the vessel, and the air ejected from this frame is adapted to dispel a fog or a heavy mist that surrounds a vessel, thus permitting a vessel proceeding upon its journey. The frames 13 assist in maintaining the equilibrium of a vessel and prevent the same from rocking. The gates 20 and 21 and the numerous valves of my device can be automatically controlled from the bridge or a similar point upon the vessel. Fresh air is supplied to the interior of a vessel and the numerous compartments thereof by funnels 23.

The utilization of compressed air for the purposes herein specified is adapted to render the vessel salvable when injured or aground. Having now described my invention what I claim as new, is:

1. The combination of a vessel having compartments formed therein, of air com-

- pressors, reservoirs for receiving air from said compressors, pipes for supplying air to the numerous compartments of said vessel, frames arranged longitudinally upon the bottom of said vessel, members at the ends of said frames for providing a compartment beneath said vessel when aground, hoods arranged in the bottom of said vessel and communicating with said reservoir, gates arranged in said hoods for controlling the direction of the discharge of air in said hoods, and a frame arranged upon the deck of said vessel for discharging air and dispelling of fog surrounding said vessel.
- 15 2. The combination with a vessel, of air compressors, reservoirs for receiving air from said compressors, pipes for delivering air to the numerous compartments of said vessel,
- 5 a frame arranged upon said vessel for discharging air and dispelling fog, and means arranged at the bottom of said vessel for ejecting air and propelling said boat.
- 10 3. The combination of a vessel, air compressors located therein, longitudinal frames carried by the bottom of said vessel, members arranged at the ends of said frames for providing a compartment beneath said vessel, and means for supplying air to said compartment from said compressors when said vessel is grounded.
- 15 In testimony whereof I affix my signature in the presence of two witnesses.

PAUL JAMNITZKY.
